US00D795433S

(12) **United States Design Patent** (10) **Patent No.:** **US D795,433 S**
(45) **Date of Patent:** **** Aug. 22, 2017**

(54) **PROSTHETIC FOOT COVER**

(71) Applicant: **Össur Iceland ehf**, Reykjavik (IS)

(72) Inventors: **Arinbjörn Viggo Clausen**, Reykjavik (IS); **Lárus Gunnsteinsson**, Reykjavik (IS); **Rowan Patrick Robinson Cain**, Kopavogur (IS)

(73) Assignee: **Össur Iceland ehf**, Reykjavik (IS)

(**) Term: **15 Years**

(21) Appl. No.: **29/566,607**

(22) Filed: **Jun. 1, 2016**

Related U.S. Application Data

(63) Continuation-in-part of application No. 14/755,464, filed on Jun. 30, 2015.

(57) **CLAIM**

We Claim the ornamental design for a prosthetic foot cover, as shown and described.

DESCRIPTION

FIG. 1 is a perspective view of an embodiment of a new design of a prosthetic foot cover;

FIG. 2 is a front view of the prosthetic foot cover of FIG. 1; FIG. 3 is a rear view of the prosthetic foot cover of FIG. 1; FIG. 4 is a right side view of the prosthetic foot cover of FIG. 1;

FIG. 5 is a left side view of the prosthetic foot cover of FIG. 1;

FIG. 6 is a top view of the prosthetic foot cover of FIG. 1; and,

FIG. 7 is a bottom view of the prosthetic foot cover of FIG. 1.

The broken lines, where shown, represent unclaimed subject matter and form no part of the claimed design.

1 Claim, 6 Drawing Sheets
